UNITED STATES PATENT OFFICE.

JOSEPH H. DOW, OF CLEVELAND, OHIO, ASSIGNOR OF ONE-HALF TO
WILLIAM CHISHOLM, OF SAME PLACE.

ROTARY STEAM-ENGINE

SPECIFICATION forming part of Letters Patent No. 392,545, dated November 6, 1888.

Application filed June 8, 1887. Serial No. 240,652. (No model.)

To all whom it may concern:

Be it known that I, JOSEPH H. Dow, of Cleveland, in the county of Cuyahoga and State of Ohio, have invented certain new and useful Improvements in Rotary Steam-Engines; and I do hereby declare the following to be a full, clear, and exact description of the invention, such as will enable others skilled in the art to which it pertains to make and use 10 the same.

My invention relates to improvements in rotary steam-engines in which the engine is of the double variety, having a casing inclosing stationary disks facing outward and rotating 15 disks facing inward, the latter being mounted on a shaft in common, and is designed more particularly as an improvement on Patent No. 360,766, granted to me April 5, 1887. The stationary disks each have two or more 20 series of curved chutes or wings arranged on the faces thereof, the chutes of each series being arranged in concentric order with the engine-shaft. The rotating disks have respectively series of curved buckets arranged 25 with the inner faces thereof in order concentric with the shaft, such series corresponding in number with the series of chutes, the different series of buckets being made to travel in annular paths between or radially outside 30 the respective series of chutes, but without contact. The chutes are slightly separated the one from the other, leaving curved passage-ways or vents between them, and the same arrangement is had with the buckets, 35 the curves of these passage-ways respectively of the chutes and buckets being in reverse order. By means of the curved vents the steam is directed against the buckets at the proper angle to propel the latter by im- 40 pact or momentum of the steam, the direction of the latter being reversed from chute to bucket and from bucket to chute throughout the system, and the series may be multiplied or compounded to any extent necessary to 45 utilize substantially the expansive energy of the steam, to the end that high speed of energy is attained and great power developed as compared with the amount of steam used, and that the energy is approximately frictionless 50 and can be made at a small initial cost per horse-power.

My invention also relates to details of con-

struction hereinafter described, and pointed out in the claims.

In the accompanying drawings, Figure 1 is 55 a side elevation of my improved engine. Fig. 2 is an elevation in longitudinal section taken through the center of the engine. Fig. 3 is an end elevation with a head and bucket-wheel removed, showing more especially the 60 relation of ways and buckets, the former being in solid lines and the latter in dotted lines; and Fig. 4 is a view in perspective of one stationary and one rotating disk, the latter being shown in section. 65

A represents the body or shell of the engine, to which are detachably secured the heads B, the latter having suitable boxes, in which is journaled the engine-shaft D. The shell A is provided with internal annular 70 flanges, a, the same being "faced off" and screw-threaded at their internal periphery to receive disks C, the latter having hub C' screw-threaded externally for engaging the screw-threads of the aforesaid flanges. With 75 this construction the disks are easily detached, and when in place are "brought true" with the other parts of the engine. The two flanges and the two disks are separated to form the steam-chamber A', the latter being in open re- 80 lation with the induction steam-pipe a'.

The disks C on the outer faces are provided with two or more series of curved wings or chutes c arranged in order concentric with the shaft D, the ends of adjacent chutes of a 85 series overlapping and slightly separated from each other to form the vent or port c'. The shaft D has mounted thereon and rigidly attached thereto a double-cone sleeve, d, the said sleeve being made slightly tapering from a 90 transverse center line toward either end, this conical feature being hardly perceptible in the drawings. The ends of the sleeve are screw-threaded and provided with nuts d'.

There are rotating disks or wheels that are mounted on the sleeved. These wheels have long hubs E', the latter being bored slightly tapering to fit, respectively, the conical sections of the sleeve d. The wheels may be forced onto the sleeve and held in position by means of the 100 nuts d', the wheels being held from turning on the sleeve by friction. With such construction the wheels may be placed upon the sleeve and faced off, and afterward may be removed 95

and reassembled in the engine without danger of losing their alignment. The wheels E have on their inner faces buckets e, arranged in concentric series, as shown in dotted lines, Fig. 3, 5 each series of buckets being made to run in annular paths had between the chutes or radially outside the chutes. The buckets are separated the one from the other, and leave vents or ports e', and these are arranged in 10 the reverse order to the vents e'. The chutes and buckets do not come in contact with each other and do not come in contact with the opposing disks and wheels; but the faces of the chutes and buckets should come as near 15 the opposing wheels and disks as is practicable and still leave working clearance, so that while these parts are relatively to each other frictionless there is practically little or no waste of steam past the faces of the buckets 20 and chutes. The inner extreme of the chamber A' is closed by sleeves F, the latter being screwed together, for instance, at f. These sleeves have external flanges, F', that overlap the outer faces of the inner series of chutes e, 25 thus closing up the vents e' of this series on the side next the opposing wheels E, so that there can be no leakage of steam past the faces of these inner chutes. These sleeves and flanges serve as clamps to hold the disk 30 E as against pressure in the steam-chamber. The sleeves F are somewhat less in diameter than the bore of the disk C. Consequently an annular space, f', is left between the edges of the disk and the sleeve, through which space 35 steam may freely pass from the chamber A' to the inner series of vents. Rings G are attached to the faces of the wheels E in position to cover the faces of the outer series of buckets, the disk C being recessed to receive 40 such rings without contact, but leaving as little space as may be between the ring and disk. These rings practically prevent any escape of steam between the faces of the outer series of buckets and the opposing 45 wheels, for the reason that the steam will take the more direct course through the larger outlets between the buckets—that is to say, through the outer vents, e', which lead direct to exhaust-chamber H, which latter dis- 50 charges into the exhaust-pipe h. This engine is driven solely by the impact of steam upon the buckets, and if some non-elastic substance—such, for instance, as water—were introduced after impact with the first series of buck- 55 ets the water would give no further motive power, but instead would obstruct and clog the engine. The steam after delivering its blows upon the first series of buckets expands, and by reason of such expansion gathers 60 momentum for impact with the next series of buckets, and so on through the successive series, or until the expansive force of the steam has been substantially utilized. The series of chutes and buckets may therefore be ex- 65 tended indefinitely, according to circumstances and according to the initial pressure of the steam employed. Now, while it is admitted

that comparatively light blows are given by impact of steam upon the buckets, the blows are very numerous and the velocity of the 70 steam is great, and by reason of the steam striking the buckets at an angle to the line of motion of the latter a still greater velocity is given to the buckets, and the lesser blows given to the outer series of buckets act at a 75 greater leverage, and are consequently effective, the high speed attained compensating for the small force of the steam acting at any given point.

What I claim is—

1. In a rotary steam-engine, the combination, with engine-shaft and a double-cone sleeve mounted on the engine-shaft, substantially as indicated, of bucket-wheels mounted on the respective conical sections of the said sleeve, 85 substantially as set forth.

2. In a rotary steam-engine, the combination, with engine-shaft and a double-cone sleeve mounted on the shaft, of bucket-wheels mounted on the said sleeve, said bucket-wheels having hubs set facing each other, said wheels and hubs having conical bores made to fit the respective conical sections of the sleeve, substantially as set forth.

3. In a rotary steam-engine, the combination, with engine-shaft and a double-cone sleeve mounted on the shaft, of bucket-wheels and attached hubs set facing each other mounted on the said sleeve, the sleeve having external screw-threads at the respective ends thereof, 100 and nuts for engaging such threads, said nuts being made to abut the respective outer faces of the bucket-wheels, substantially as set forth.

4. In a rotary steam-engine, the combination, with stationary disks and intervening steam-chamber, substantially as indicated, of sleeves for closing the inner periphery of the steam-chamber, said sleeves being screwed together and having external flanges made to clamp the disks as against internal pressure, 110 substantially as set forth.

5. In a rotary steam-engine, the combination, with stationary disks and intervening steam-chamber, said disks having series of chutes and vents arranged thereon, substantially as indicated, of sleeves made to close the inner periphery of the steam-chamber, said sleeves having external flanges made to cover the faces of the inner series of chutes, substantially as set forth.

6. In a rotary steam-engine, the combination, with stationary disks, chutes, and vents, and rotary wheels with buckets, substantially as indicated, of rings made to cover the faces of the outer series of buckets, said stationary 125 disks having recesses to receive such rings, substantially as set forth.

In testimony whereof I sign this specification, in the presence of two witnesses, this 28th day of May, 1887.

JOSEPH H. DOW.
